UNITED STATES PATENT OFFICE.

CHARLES W. GRAHAM, OF HUNTINGTON, NEW YORK, ASSIGNOR TO AMERICAN CAN COMPANY, OF NEW YORK, N. Y., A CORPORATION OF NEW JERSEY.

CAN-END-LINING MACHINE.

1,343,913.

Specification of Letters Patent. Patented June 22, 1920.

Application filed March 1, 1916. Serial No. 81,315.

To all whom it may concern:

Be it known that I, CHARLES W. GRAHAM, a citizen of the United States, residing in Huntington, in the county of Suffolk and State of New York, have invented a new and useful Improvement in Can-End-Lining Machines, of which the following is a specification.

This invention relates in general to can end lining machines and has more particular reference to can end lining machines which apply a previously cut out or formed liner to the can ends. It will, however, be manifest, as the invention is better understood, that numerous features of it may have valuable application in can end lining machines wherein the liners are cut and applied in the same machines or as closely successive operations. Can end liners are frequently of fibrous material such as paper and in the form of delicate rings of large diameter which are easily distorted or torn in handling, and a mechanism to operate upon them effectively should be deliberate and certain in its action. A principal object of this invention is the provision of a can end lining machine wherein the operation of the individual parts of the machine may be relatively slow and unhurried and the machine at the same time have a relatively high capacity.

A further object of this invention is the provision of a can end lining machine which is capable of moving the liners through an opening above the liner seat in the can end which is smaller than the liner, so that the machine may be used with can ends in which the annular seaming flange extends inwardly over itself slightly as is sometimes desirable.

A further object of the invention is the provision in such a machine of means for accurately and positively taking a can end and a can end liner from separate stacks and which, after depositing them in proper relative positions, will assemble them into a unitary article.

A still further object of the invention is the provision of such a machine consisting of few and simple parts and adapted to operate upon a number of can ends simultaneously.

Other objects and advantages of the invention will be apparent as it is better understood from the following description

when considered in connection with the accompanying drawings illustrating a preferred embodiment thereof.

Referring to the drawings,

Figure 1 is a vertical front view of a machine embodying this invention;

Fig. 2 is a side view looking at the right hand side of Fig. 1;

Fig. 3 is a vertical sectional view taken on the line 3—3 of Fig. 1 and looking in the direction of the arrows;

Fig. 4 is a horizontal sectional view taken along the line 4—4 of Fig. 1, showing the multiple arrangement of the machine;

Fig. 5 is a horizontal sectional view taken along the line 5—5 of Fig. 3 and looking in the direction of the arrows, with parts broken away to more clearly show underlying parts; the right side of the view showing the cut ring and can end feed slides moved to their inner positions;

Fig. 6 is an enlarged vertical sectional view taken on line 6—6 of Fig. 4 looking in the direction of the arrows and showing the ring chute, cut rings therein, and the recessed reciprocating feed slide for feeding the rings from the ring chute to the assembling station;

Fig. 7 is a vertical sectional view taken on line 7—7 of Fig. 4 looking in the direction of the arrows, and showing an assembling plunger, a cut ring can end liner, and a can end, all in assembling position, the assembling plunger having descended into contact with the ring, a further downward movement resulting in pushing the flexible can end liner past the annular shoulder on which it rests, down into the recess of the positioned can end;

Fig. 8 is a vertical sectional view taken along line 8—8 of Fig. 1 showing in detail the mechanism for effecting the discharge of the completed and lined ends;

Fig. 9 is an enlarged detail section showing a ring liner seated in the liner slide;

Fig. 10 is a similar view showing it entering in the liner-receiving groove in the can end; and

Fig. 11 shows it in place upon the liner-receiving groove in the can end.

The machine embodying my invention and shown on the drawings is adapted to apply liners to a number of can ends simultaneously, and to this end there is provided a plurality of assembling stations arranged

- side by side and in a straight line, four being chosen for the purpose of illustrating this invention. At one side and parallel with the assembling stations is arranged a plurality of vertical can end stacks under which reciprocates a feed slide which automatically takes four can ends from these stacks and positions them simultaneously at the assembling stations, one at each station.
- 10 At the opposite side and parallel with the assembling stations is arranged a plurality of vertical stacks of cut ring liners under which a feed slide reciprocates, which feed slide automatically carries four ring liners and positions them at the assembling stations directly over and in vertical alinement with the previously positioned can ends.
- 15 When thus arranged the slides are quiescent while a plurality of assembling plungers move against the ring liners and push them vertically downwardly into the liner-receiving recesses of the can ends. As these plungers retreat the slides return for subsequent charges of can ends and liners and as 20 the plungers reach the end of their upward or retreating stroke the supports beneath the lined can ends are withdrawn, permitting the can ends to be dropped upon a conveyor carrying them out of the machine.
- 25 The foregoing brief description applies, however, only to the machine shown on the drawing, which may be varied in many ways without departing from the scope or spirit of the invention.
- 30 Referring to the drawings, reference character A indicates what may be termed the main frame of the machine. This frame comprises suitable standards or legs a^1 supporting a bed a^2 . From this bed a standard a^3 extends upwardly from each side and provides a bearing a^4 for a power shaft B having at one end a driving pulley b^1 through which is transmitted the power necessary to the operation of the machine.
- 35 Feeding mechanisms are provided to feed the can ends and the can end liners simultaneously and in a horizontal plane to an assembling station where the liners are placed in the can ends. Two slides C and D are mounted upon the upper face of the bed and move toward and from each other in the operation of the machine. One of these slides, D, carries can ends and the other, C, can end liners into assembling position.
- 40 The liners E and the can ends F are taken respectively from stacks held in stack supports formed of vertically extending rods f^1 e^1 and vertically extending plates f^2 e^2 . These stack supports are secured upon and extend upwardly from a plate G mounted above the bed a sufficient distance to permit the slides to move just under it. The rods e^1 f^1 and plates e^2 f^2 are in number and arrangement such as to constitute four stack supports for can end stacks f^3 at one side

and four stack supports for can end liner stacks e^3 at the other side. The plate G is provided with four apertures g^1 beneath the can end supports, in which apertures the bottoms of the stacks of can ends repose in position to have the lowermost can end of each stack removed by the slide D as it advances toward the assembling station. Four similar apertures g^2 are located beneath the stacks of liners and these stacks also extend into the apertures, so that the lowermost liner of each stack may be taken by its slide C to the assembling station. The slides C and D receive their power from the shaft B, and this through the medium of a cam b^2 engaging a roller b^3 upon one arm of a bell crank b^4 pivoted at b^5 on a standard a^3 and having pivotally connected to its other arm two links b^6 and b^7 . The link b^6 is connected to a bell crank b^8 which, through a link b^9 , connects with the slide C. The link b^7 is similarly connected through a bell crank b^{10} and link b^{11} with the slide D, these link and bell crank mechanisms being so arranged as to cause the slides to simultaneously move 80 toward each other on their operative stroke and back away from each other on their inoperative stroke.

The assembling stations are located between the two series of stack supports and the slides are arranged and constructed so that the ring liner carrying slide C moves over the can end carrying slide D at the assembling station.

The can end carrying slide D (see Figs. 100 5 and 7) is comprised in the present instance of a plate d^1 having four semi-circular recesses d^2 in its edge adjacent the slide C, each recess being adapted to engage a can end at the bottom of a stack when the slide is moved in its operative stroke. The slide D moves upon the bed a^2 and is provided with four tongues d^3 , one extending out and from beneath the center of each recess, these tongues being adapted to provide a positive support for the can end. The slide C, which carries the can end liners, (see Figs. 5 and 6) consists of a plate c^1 having four apertures c^2 each adapted to select the bottom-most liner of an appropriate stack and carry it forwardly over a can end carried by a recess d^2 and tongue d^3 . Each aperture c^2 is of size at its top equal to the over-all diameter of a ring liner. An inwardly extending lip or flange c^3 is provided in each aperture c^2 a distance beneath its top equal to the thickness of a liner, so that single liners may be selected by the slide as it starts movement on its forward stroke. The flanges c^3 extend inwardly only a slight distance and beneath them the diameter of the aperture is equal substantially to the outer diameter of a ring liner. Viewing Figs. 5 and 7 it will be noted that the bed a^2 is cut away to provide guideways a^5 130

for the tongues d^3 , and the slide C, which is much thicker than the slide D, is cut away at one side at c^4 to permit the plate d^1 to enter beneath it and position four can ends F in 5 vertical axial alinement respectively with the four recesses c^2 and the ring liners E carried upon the inwardly extending flanges e^3 thereof. When the slides have arrived thus at the assembling station the cam b^2 10 causes them to remain quiescent. Four plungers, part of an assembling mechanism, generally designated at H position the liners in the can ends. These plungers are mounted in a cross-head h^1 which is movable in 15 guides h^2 on the standards a^3 . The cross-head receives its movement from the power shaft B through two eccentrics h^3 and driving rods h^4 pivoted to the cross-head. Each plunger comprises a head h^5 and a stem h^6 secured in a socket h^7 in the cross-head h^1 . Outside diameter of the plunger head h^5 is somewhat smaller than the diameter of the opening through the flange c^3 . When the slides have reached their inner position 20 and are at rest, each plunger moves downwardly and engages the ring liner carried by the slide C and forces it past the flange c^3 . It carries it on downwardly to the can end beneath it and forces it past the upturned edge f^{11} of the flange f^{12} on which the liner seats, as will be later described more in detail. Thereafter the plungers move back out of the slides and the slides 25 separate and return to receive a succeeding set of can ends and can end liners, leaving the lined can ends at the assembling station. An aperture a^6 is provided through the bed beneath each can end, and through this aperture the lined can ends are discharged. 30 Prior to their discharge, however, and in order that they may drop accurately through the apertures, two bars l^1 and l^2 acting under pressure of springs s^1 extend across the machine in recesses a^7 and a^8 35 therein, these parts closing the apertures a^6 to a sufficient extent to prevent the can ends dropping through. As the plungers reach the upper end of their stroke the bars l^1 and l^2 are caused to move apart by a pair of 40 wedge blocks l^3 (see Figs. 5 and 8). Each 45 of these wedge blocks is carried on the end of a stem l^4 secured in a socket l^5 in the cross-head, and only when the cross-head is in the uppermost position are the larger 50 parts of the wedge blocks moved between the bars l^1 and l^2 to separate them. As the plungers near the top of their stroke, the bars l^1 and l^2 are moved apart and the can 55 ends drop upon a conveyer M which carries them outside the machine. The can end shown on the drawing is provided with a shoulder f^{14} flaring outwardly slightly from the central part of the can end to the liner seat, and the internal diameter of the 60 liner is preferably less than the largest di- 65 ameter of the shoulder. The plunger will wedge the liner tightly and positively in place by forcing it down about this tapering shoulder. The edge of the liner is bent back to pass the edge f^{11} of the peripheral 70 flange of the can top (Fig. 10) but not sufficiently to prevent its springing back to its original position as it approaches its seat. Where the liner is wedged down tightly 75 about the shoulder of the can end or its forward edge is disposed behind the edge f^{11} or both, the liner is prevented from being displaced in handling or in transferring the can end from the liner applying machine to a machine for applying it to a can 80 body forming a unitary article.

It will be manifest from the foregoing that the machine may be constructed to operate upon any number of can ends simultaneously and any desired capacity therefore given it without increasing the time of operation required for the placing of a liner in an individual can end.

It is thought that the invention and many of its attendant advantages will be understood from the foregoing description, and it will be apparent that various changes may be made in the form, construction and arrangement of the parts without departing from the spirit and scope of the invention or sacrificing any of its material advantages, the form hereinbefore described being merely a preferred embodiment thereof.

I claim:

1. In a machine for applying can end liners to the flanges of shouldered can ends, for the production of interfolded hermetic seams with flanged can bodies, the combination of a stack holder for holding a stack of superimposed previously cut ring liners, a combined feeding and supporting device having a through aperture for selecting liners singly from said stack and carrying them, while supported, to an assembling station, and an assembling mechanism at the assembling station having means for forcing the selected liners through said aperture and assembling said liners with can ends.
2. In a machine for applying can end liners to the flanges of shouldered can ends, for the production of interfolded hermetic seams with flanged can bodies, the combination of a stack holder for holding a stack of superimposed previously cut ring liners, a combined feeding and supporting device consisting of a shouldered orificed slide for selecting liners singly from said stack and carrying them, while supported, to an assembling station, and an assembling mechanism at the assembling station having means for forcing the selected liners through the orifice of the slide and assembling said liners with can ends.

3. In a machine for applying can end liners to the flanges of shouldered can ends, for the production of interfolded hermetic seams with flanged can bodies, the combination of a stack holder for holding a stack of superimposed previously cut ring liners, a combined feeding and supporting device, comprising a reciprocable slide member having a shouldered orifice of less diameter than the liners which embraces the ring liners around all parts of their edges, for selecting liners singly from said stack and carrying them, while supported, to an assembling station, and an assembling mechanism at the assembling station having means for forcing the selected liners through said orifice and assembling said liners with can ends.

4. In a machine for applying can end liners to the flanges of shouldered can ends, for the production of interfolded hermetic seams with flanged can bodies, in combination: can end feed mechanism and can end liner feed mechanism, reciprocable in straight lines in a horizontal plane toward each other to an assembly station, and assembling mechanism; means for reciprocating said feed mechanisms whereby a can end and a previously formed can end liner are brought into axial alinement with each other and the assembling means; and mechanism for reciprocating said assembling means to assemble said cut liner and said can end, whereby the said can end liner is deposited around the shoulder of said can end and rests on the liner seat of said can end.

5. In a machine for applying previously formed can end liners to the flanges of shouldered can ends, for the production of hermetic interfolded seams with flanged can bodies, in combination: a can end liner stack holder; horizontally movable can end feed mechanism for feeding singly, shouldered can ends, and horizontally movable feed mechanism for feeding singly from the bottom of said stack, previously formed can end liners of less diameter than the diameter of the said can ends, and of internal diameter adapted to pass over the exterior of the shoulder of the said can ends, into axial alinement with each other, and into axial alinement with assembling mechanism; means for moving said assembling mechanism whereby the shoulders of said

can ends are inserted within the can end liners and the liners and flanges of the can ends are thus assembled into unitary articles, said liner and can end feed mechanisms operating in straight lines toward each other.

6. In a machine for applying previously formed can end liners to the flanges of shouldered can ends, for the production of hermetic interfolded seams with flanged can bodies, in combination: a can end liner stack holder; horizontally movable can end feed mechanism for feeding singly shouldered can ends, and horizontally movable feed mechanism for feeding singly, previously formed can end liners of less diameter than the diameter of the said can ends, and of internal diameter adapted to pass over the exterior of the shoulder of the said can ends, into axial alinement with each other, and into axial alinement with assembling mechanism, the can end liner feed mechanism having a member operating under said stack holder and having a recess which embraces the liner exteriorly and a shoulder which supports the outer part of the liner; means for moving said assembling mechanism whereby the shoulders of said can ends are inserted within the can end liners and the liners and flanges of the can ends are thus assembled into unitary articles; and means for automatically discharging the said lined can ends, said liner and can end feed mechanisms operating in straight lines toward each other.

7. In a machine for applying previously formed can end liners to the flanges of shouldered can ends, for the production of hermetic interfolded seams with flanged can bodies, in combination: a reciprocable support for the can end, a reciprocable support for the liner, said support having an opening through which said liner may be moved, said opening being of diameter less than the diameter of said liner, said supports being movable toward and into line with each other and means for moving said liner through said opening.

In testimony whereof I have hereunto set my hand in the presence of two subscribing witnesses.

CHARLES W. GRAHAM.
